UNITED STATES PATENT OFFICE.

PHILIP C. P. BOOTY, OF CHICAGO, ILLINOIS, ASSIGNOR OF ONE-HALF TO MICHAEL T. DALEY, OF CHICAGO, ILLINOIS.

CONTAINER.

Application filed January 31, 1927. Serial No. 164,749.

My invention relates to containers of a type adapted to hold liquid or powder contents and to dispense the same in small quantities, and it is one of the objects of my invention to provide a new and improved form and arrangement of parts for accomplishing this result. My invention relates to the general form of device shown and described in my co-pending application 10 Serial No. 97,253, filed March 25, 1926, and it is shown as applied to a perfumery container (see Fig. 5) or as applied to any bottle or other container for liquid which it is desired to feed out gradually.

It is one of the objects of my invention to simplify the construction of the closure means of the container so that it can be manufactured on a commercial basis with the utmost ease; to which end it is one of the 20 objects of my invention to form the closure coil in the most easily formed shape and to provide for the desired closing of the several plies of the coil into snug contact with each other independently of any resiliency of the 25 coil.

It is another object of my invention to provide for the application of my improved closure means to any ordinary bottle or similar container without any change in the 30 container, being applied in complete operative form to the cork or other stopper device for the container. It is still another object of my invention to improve devices of this character in sundry details herein-after pointed out. The preferred means by which I have accomplished my several objects are illustrated in the accompanying drawing and are hereinafter specifically described. That which I believe to be new 40 and desire to cover by Letters Patent is set forth in the claims.

In the drawing,—

Fig. 1 is a central vertical section through one form of my improved device applied to a bottle.

Fig. 2 is a view similar to Fig. 1 but with the protecting cap removed and with the parts in changed position for discharging a quantity of the contents of the bottle against a pad.

Figs. 3 and 4 are views similar to Fig. 1 but showing respectively modified forms of construction; and

Fig. 5 is a central vertical section through

a modified form of device applied to a 55 special form of container for perfumery or the like.

Referring to Figs. 1 and 2,—10 indicates the neck and mouth portion of a bottle having removably secured therein a stopper 60 comprising a metal part 11 equipped with an adapter 12 of cork or other suitable material for securing the desired close fit in the neck 10. As will be readily understood, adapters of various size and shape can be 65 substituted in place of the adapter 12 for making the stopper suitable for use with receptacles of various sizes without any change in the receptacle and with a standard part 11 in use.

The stopper member 11 is provided with a discharge opening 13 therethrough, in the upper end of which a nipple 14 in the shape of a sleeve is removably secured by means of screw threads. A coil 15 is connected at 75 one end with the lower end of the discharge opening of the nipple 14, the lower end of the coil 15 being closed by a suitable head 16 which serves to secure in position a pin 17 which extends through the coil. The 80 head 16 is preferably in the form of a quantity of solder by which the pin 17 is firmly secured in position. A yoke 18, preferably of sheet metal, is secured at its end portions to the nipple 14 and extends about the 85 lower end of the coil 15, with a coiled spring 19 interposed between the head 16 and the lower end of the yoke, the arrangement being such that the spring 19 serves to hold the several plies of the coil 15 in snug contact with each other for forming a tight closure between the pin 17 and the inner face of the sleeve or nipple 14. A cap 20 is removably secured, preferably by screw threads, upon the outer end of the nipple 14 90 about the projecting end of the pin 17, as is clearly shown in Fig. 1.

When it is desired to discharge from the bottle 10 a small quantity of the liquid or powder contents thereof, the cap 20 is to be 100 removed from the nipple 14; the bottle is then to be inverted so as to bring the outer end of the pin 17 into contact with a pad 21 or other part upon which the contents are to be discharged, the pin 17 being moved inwardly against the action of the spring 19 by pressure upon the pin from the pad. 105 This inward movement of the pin 17 serves

to spread the plies of the coil 15 for permitting the escape of a quantity of the liquid or powder from the bottle.

By the provision of a coil of the type shown in Fig. 1 in which the several plies are of substantially the same size so as to make the coil of substantially cylindrical form, the production of the coil upon a commercial scale is made as easy as possible, requiring practically no special parts. By the provision of a separate spring 19 for normally holding the plies of the coil in operative closing contact with each other, I am enabled to make the coil 15 of comparatively soft material, thus further increasing the ease of the manufacturing operation. By making the dispensing device in the form of a complete operative unit capable of being removably secured by means of screw threads or otherwise in any discharge opening, I have made it easy to adapt the device to use with many different forms and sizes of container. By the provision of the adapter 12, I have provided for the use of the device for closing any ordinary bottle opening by the mere substitution of an adapter of suitable size in place of the adapter 12.

The construction shown in Fig. 3 is substantially the same as that above described, except that a spring 22 is substituted in place of the spring 19, such spring 22 being held in position by means of a nipple 23 secured by screw threads in the lower end of the stopper member 24, such spring 22 bearing at its upper end upon a head 25 of greater diameter than the head 16 of the device above described. In this construction, a pin 26 is provided of shorter length than the pin 17 of the first described device, since the spring 22 is sufficiently supported by the nipple 23. A nipple 27 is substituted in place of the nipple 14, such nipple 27 being of a rounded conformation on its upper face rather than being of the cylindrical type for supporting a protecting cap as is illustrated in Fig. 1. The operation of the device of Fig. 3 is the same as that above described, and does not, therefore, require further description.

In the construction shown in Fig. 4, a metal stopper 28 is employed in lieu of the metal and cork stopper of the device of Fig. 1, such metal stopper 28 being secured by means of screw threads in the upper end of the neck of a bottle 29. The upper end of a coil 30 is secured to a nipple 31 which is held in position within the discharge opening of the stopper 28 by means of screw threads. The operating pin 32 is secured by means of a head 33 of solder or other suitable material to the lower end of the coil 30. In the embodiment shown in this figure, the coil 30 is made of spring material wound in such manner that the resiliency of the coil itself serves to hold the several plies of the coil 30 yieldingly in snug contact with each other

so as to form an effective closure between the pin 32 and the inner face of the opening through the nipple 31.

In Fig. 5, the construction is very similar to that shown in Fig. 4, except that the nipple 35 to which the spring coil 30 is secured is mounted by means of screw threads directly in the upper ends of the metal casing 36 rather than being secured by the use of an interposed cork or stopper.

While I have shown the closure coil in each instance secured in position with its stationary end disposed outwardly and with the inner end of the coil movable inwardly therefrom by an inward pressure upon an operating part in the form of a pin, it will be understood that I do not limit my invention to this form of device except so far as certain of the claims are specifically so limited, the essential feature being that the coil shall serve normally to act as a closure and shall be distorted by pressure thereon for permitting the escape of a limited quantity of the contents of the container. Neither do I wish to limit my invention to other details of construction except as certain of the claims may be so limited, since it will be evident that changes may well be made in the form and construction of the device without departing from the spirit of my invention.

I claim:

1. A closure member for the opening into a container, comprising a substantially cylindrical coil mounted in said opening and having a plurality of plies in alignment with each other longitudinally of the coil serving by contact with each other along the coil to close said opening, and means for spreading said plies slightly out of operative contact with each other.

2. A closure member for the opening into a container, comprising in combination a coil mounted in said opening and having a plurality of plies overlying each other in progressively extended position along the axis of the coil serving by contact with each other to close said opening, and yielding means serving normally to hold the plies of the coil yieldingly in operative closing position.

3. A closure member for the opening into a container, comprising in combination a coil mounted in said opening and having a plurality of plies overlying each other in progressively extended position along the axis of the coil serving by contact with each other to close said opening, and a spring serving normally to compress the coil for holding its plies in operative position.

4. A closure member for the opening into a container, comprising in combination a nipple in the form of a sleeve removably secured in said opening, a coil mounted at one end in the opening of said sleeve, a pin secured to the opposite end of the coil and ex-

tending through the coil and through the opening in the sleeve, the several plies of the coil serving by contact with each other to close the space between the pin and the inner 5 face of the sleeve, and a cap removably mounted on said nipple about the projecting end of the pin.

5. A closure member for the opening into a container, comprising in combination a coil 10 mounted in said opening and having a plurality of plies overlying each other in progressively extended position along the axis of the coil serving by contact with each other to close said opening, a yoke extending about 15 the end of the coil, and a spring interposed between the yoke and the coil serving normally to compress the coil for holding its plies in operative closing position.

6. A closure member for the opening into 20 a container, comprising in combination a nipple in the form of a sleeve removably secured in said opening, a coil mounted at one end in the opening of said sleeve, a pin secured to the opposite end of the coil and 25 extending through the coil and through the opening in the sleeve, the several plies of the coil serving by contact with each other to close the space between the pin and the inner 30 face of the sleeve, a yoke carried by said nipple and extending about said coil, and a spring interposed between the yoke and the coil serving normally to compress the coil for holding the several plies in operative closing 35 position.

7. A closure for the filling opening into a container, comprising in combination a stopper member having a discharge opening therethrough, an adapter about said member for fitting it to said filling opening, and a 40 coil mounted in said discharge opening and having a plurality of plies overlying each other in progressively extended position along the axis of the coil and serving by contact with each other in such progressively 45 extended position to close said discharge opening.

8. A closure for the filling opening into a container, comprising in combination a stopper member having a discharge opening therethrough, an adapter about said member 50 for fitting it to said filling opening, and a

coil of substantially cylindrical form mounted at one end in said discharge opening and having a plurality of plies serving by contact with each other along the coil to close said 55 discharge opening.

9. A closure for the filling opening into a container, comprising in combination a stopper member having a discharge opening therethrough, an adapter about said member 60 for fitting it to said filling opening, a nipple in the form of a sleeve removably secured in said discharge opening, a spring coil secured at one end to said nipple and extending inwardly therefrom having a plurality of plies 65 serving by contact with each other to close the opening through said sleeve, and a pin secured to the inner end of the coil and extending outwardly through the nipple for 70 pressing the plies apart.

10. A closure for the filling opening into a container, comprising in combination a stopper member having a discharge opening therethrough, an adapter about said member for fitting it to said filling opening, a nipple 75 in the form of a sleeve removably secured in said discharge opening, a spring coil secured at one end to said nipple and extending inwardly therefrom having a plurality of plies serving by contact with each other to close 80 the opening through said sleeve, a pin secured to the inner end of the coil and extending outwardly through the nipple for pressing the plies apart, and a coiled spring also supported from said nipple serving normally 85 to assist in pressing the plies of said first named spring coil into operative closing contact with each other.

11. A closure member for the opening into a container, comprising in combination a 90 stopper member having an opening therethrough, a coiled spring of substantially cylindrical form secured at one end in the opening in said stopper member and having a plurality of plies serving by contact with 95 each other to close the opening, and a pin carried by the free end of said coil and extending therethrough for spreading the several plies apart for the discharge of contents from the container.

PHILIP C. P. BOOTY.
